UNION SUIT OR COMBINATION-GARMENT.

1,092,809.

Specification of Letters Patent.

Patented Apr. 7, 1914.

Application filed November 9, 1912. Serial No. 730,354.

To all whom it may concern:

Be it known that we, EDWARD H. DAVISON and EDWARD L. DUMMER, citizens of the United States, residing at New Britain, in the county of Hartford and State of Connecticut, have invented certain new and useful Improvements in Union Suits or Combination-Garments, of which the following is a specification.

10 Our invention relates to improvements in union suits or combination garments, and the objects of our improvements are ease and comfort of the wearer with freedom from undue strain on the seams of the suit, and 15 otherwise rendering the suit more durable.

In the accompanying drawing: Figure 1 is a front view of a union suit constructed in accordance with our invention. Fig. 2 is a rear view of the same. Fig. 3 is a broken off rear view of the same with the drop seat let down. Fig. 4 is a broken off rear view of the union suit as slit in the seat and legs ready for having the drop seat and its gussets secured thereto. Fig. 5 is a plan view of the smaller gusset. Fig. 6 is a plan view of the combined flap and larger gusset. Figs. 7, 8 and 9 are broken off views of the suit on a form showing the seat or flap let down, while the belt is drawn together in 20 front, the flap closed while the belt is detached in front, and the flap closed and the belt drawn taut at the front, respectively.

Our improvement is applicable to union suits made in any ordinary manner from 25 either woven or knitted fabric. As shown our suit is made from knitted fabric which is first made into an ordinary union suit provided with a slit or opening in the seat and is also slit from the crotch down on 30 the legs as illustrated in Fig. 4. If the suit is fashioned knit the slit will have a selvage edge but if it is cut it may be bound or hemmed to properly finish the edges. Instead of attaching ordinary laps to the edges 35 of the material at the back we leave the said edges free with suitable finish and provide a special form of drop seat which is attached as hereinafter described. The drop seat 40 we prefer to make fashioned knit with swallow tail gusset points 11 at its lower end and we form the junction 12 of the two points in the form of a curved loop as shown in Fig. 6, instead of having the

inner edges meet within an angle. Within the swallow tail we secure a smaller gusset 55 13 that comes to a point at each end and provided with a curved extension 14 on one edge of its middle portion as shown in Fig. 5. This smaller gusset 13 which is set in the crotch of the suit is preferably made of 60 heavy material instead of making it of two thicknesses as gussets for the seat have sometimes been made. After the drop seat and gussets have been prepared as shown in Figs. 5 and 6 we secure the smaller gusset 65 13 within the swallow tail points by securing the curved extension 14 and adjacent edges to the inner edges of the gusset points of the drop seat. We then secure the combined flap and gussets to the suit as prepared in Fig. 4, by securing the inner edges 70 to the edges of the slit in the drawer legs as at 15, Figs. 1 and 3, and their outer edges to outside of the legs beyond the edges of the slit as at 16, Fig. 2 and securing the edges 75 of the slit in the legs to the body of the gusset points as at 17, Fig. 2. The gussets as thus formed are made full enough so as to enlarge the suit through the crotch and seat at the front of the suit as well as at 80 the rear, thus giving ample room at the point where there is usually the most strain. By making the seam at the edges of the gussets with a curved extension of a loop form instead of a straight seam at the 85 crotch we avoid any possible cross strain that can pull lengthwise of the seam, whereby the strain comes on the elastic body of the material and not directly upon an inelastic seam. We thus avoid all liability of 90 breaking the threads in this seam of the gusset.

At the upper edge of the drop seat we secure a short belt 18 and provide the same at each end with a button hole 19 for connecting it to the buttons 20 on the suit near the hips. In order to make the upper edge of the drop seat fit the back neatly without any button directly at the back we provide the suit with belt extensions 21 secured by 95 their ends to the suit at each side, the button 20 herein before named being secured to the said ends. These belt extensions are provided with a plurality of button holes by which they may be secured to a central button 22 at the front for drawing the ends 100 105

of the complete belt together to make it taut and bring the upper edge of the drop seat closely within the hollow of the back as shown in Fig. 9. When the belt is thus drawn taut to properly fit the wearer it is optional whether he will unbutton the belt both in front and at the hips or at the hips only, when it is desired to let down the drop seat.

10 We claim as our invention:—

1. In a union suit having the back above the waist closed and below the waist slit to form an opening and the legs slit for the reception of a gusset, a drop seat having 15 swallow tail points with a curved loop like edge at their junction and a smaller gusset fitted and secured to the inner edges of the said points, the said seat being secured to the said suit by seams that extend down on 20 the legs at both the front and the rear thereof and with the seam at the adjoining edges

of the gussets extended across the crotch on a loop like curved line.

2. In a union suit having a drop seat, a short belt at the upper edge of the said seat 25 with a button hole at each end and a pair of belt extensions having take up devices at their front ends, and buttons on their opposite ends whereby the short belt at the upper edge of the drop seat may be connected with 30 the said extension to form a complete belt.

3. In a knit garment, a gusset embodied therein and having the general form of a lozenge with a rounded extension in the middle of its length at the junction of two 35 side edges.

EDWARD H. DAVISON.
EDWARD L. DUMMER.
